(57) **CLAIM**

The ornamental design for a front bumper for automobile, as shown and described.

DESCRIPTION

FIG. 1 is a perspective view of a front bumper for automobile; showing our new design;

FIG. 2 is a front elevation view thereof;

FIG. 3 is a right side elevation view thereof;

FIG. 4 is a left side elevation view thereof;

FIG. 5 is a top plan view thereof; and,

FIG. 6 is a bottom plan view thereof.

The broken lines in the drawings illustrate portions of the front bumper for automobile that form no part of the claimed design.
